(57) **CLAIM**

The ornamental design for an intracardiac ultrasound catheter handle, as shown and described.

DESCRIPTION

FIG. 1 is a perspective view of an intracardiac ultrasound catheter handle showing my new design;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines in the drawings showing elements of the intracardiac ultrasound catheter handle represent unclaimed portions of the intracardiac ultrasound catheter handle and form no part of the claimed design.

1 Claim, 6 Drawing Sheets
